R. C. Levacy, 7331 E. King Place, Tulsa, Okla.

Filed July 23, 1959, Ser. No. 56,903

Term of patent 14 years

(Cl. D71—1)

FIG. 1

FIG. 2

FIG. 3

FIGURE 1 is a top plan view of an anchor line clamp for boats or the like.

FIGURE 2 is a side elevational view thereof, the opposite side being substantially the same as the side shown;

FIGURE 3 is an end elevational view thereof, looking toward the right hand end of FIGURE 2.

The dominant features of my design reside in the portions shown in full lines.

I claim:

The ornamental design for an anchor line clamp for boats or the like, substantially as shown and described.
